0-1. OR D 7,770 EX

F. KROEGER

PATENTED SEPT. 22, 1874

D- 7,770

FILED AUG. 15, 1874

UNITED STATES PATENT OFFICE.

FLORENCE KROEBER, OF HOBOKEN, NEW JERSEY.

DESIGN FOR CLOCK-CASES.

Specification forming part of Design No. 7,770, dated September 22, 1874; application filed August 15, 1874.
[Term of Patent 3½ years.]

CASE E.

To all whom it may concern:

Be it known that I, FLORENCE KROEBER, of Hoboken, in the county of Hudson and State of New Jersey, have invented a new and original Design for a Clock, of which the following is a specification:

The accompanying engraving represents a face view of my new design for a clock.

This invention relates to a new configuration of the case for a pendulum-clock.

The straight sides of the case are flanked by balusters *a a*, which rest upon the base *b*.

The top of the case is in form of a gable roof without a point, a vase-like ornament, *e*, being placed upon a key-stone, *d*, in the space left between the interrupted sides of the roof.

I claim as my invention—

The design for the configuration of a clock, as shown.

F. KROEBER.
